UNITED STATES PATENT OFFICE.

FRANK YOKEL, OF HARTFORD, CONNECTICUT.

DESIGN FOR A TOY BANK.

58,862.

Specification for Design.

Patented Aug. 30, 1921.

Application filed April 26, 1921. Serial No. 464,702. Term of patent 7 years.

To all whom it may concern:

Be it known that I, FRANK YOKEL, a citizen of the United States, residing at Hartford, in the county of Hartford and State of Connecticut, have invented a new, original, and ornamental Design for Toy Banks, of which the following is a specification, reference being had to the accompanying drawing, forming part thereof.

The figure shows the toy bank in perspective.

I claim:

The ornamental design for a toy bank, as shown.

FRANK YOKEL.

In presence of—

E. O. BAUNICY,
HEATH SUTHERLAND.
